CLAIM

The ornamental design for a ball tension holder, as shown and described.

DESCRIPTION

FIG. 1 is a top-front-left perspective view of a ball tension holder showing my new design;

FIG. 2 is a bottom-rear-right perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an exploded top-front-left perspective view thereof; and,

FIG. 10 is an exploded bottom-rear-right perspective view thereof.

1 Claim, 10 Drawing Sheets
